[57] **CLAIM**

The ornamental design for a turning utensil for barbecues, substantially as shown and described.

DESCRIPTION

FIG. 1 is a front perspective view of a turning utensil for barbecues showing my new design;

FIG. 2 is a side elevational view thereof, from one side, and

FIG. 3 is a side elevational view thereof, from the opposite side,

FIG. 4 is an enlarged top plan view, and

FIG. 5 is a similarly enlarged bottom plan view thereof.

Fig. 1.
